UNITED STATES PATENT OFFICE.

CHARLES E. ONGLEY, OF NEW YORK, N. Y.

BUTTONHOLE-SEWING ATTACHMENT FOR SEWING-MACHINES.

No. 894,977.

Specification of Letters Patent.

Patented Aug. 4, 1908.

Application filed March 10, 1906. Serial No. 305,296.

To all whom it may concern:

Be it known that I, CHARLES E. ONGLEY, a citizen of the United States, and resident of the borough of Manhattan, in the county of 5 New York and State of New York, have invented certain new and useful Improvements in Buttonhole-Sewing Attachments for Sewing-Machines, of which the following is a specification.

10 This invention relates to a button hole sewing attachment for sewing machines. Its organization comprises means that can be easily attached to a sewing machine, and with which the stitches for a button hole can 15 be readily sewed.

It comprises essentially a clamping device for holding the goods to be sewed, and means for moving said device in an approximately oval path, under the point of the needle of 20 the sewing machine to which it is attached.

In the accompanying drawings, Figure 1 represents a plan view of the invention, Fig. 2 shows a front elevation of Fig. 1, with a fragmentary portion of a sewing machine 25 partly in section, Fig. 3 is a section of Fig. 1 on the line 3, 3, Fig. 4 shows a partial section of Fig. 1 on the line 4, 4, Fig. 5 represents a partial section of Fig. 1 on the line 5, 5, Fig. 6 shows an end view of Fig. 1 looking in the 30 direction of the arrow 6, Fig. 7 represents a plan view of the bed plate of the invention, with some of its appurtenances.

The invention is represented to comprise a bed plate or frame 20, which is secured to the frame 21 of a sewing machine with the screws 22. On the bed plate 20 are fastened guides 23 with the screws 24, that guide the main sliding plate 25, from which latter extends the lug 26, that carries the pin 27 for the link 28. Arms 29 extend from the main sliding plate 25, on the ends of which are formed bosses 30, which latter have openings for the longitudinal guide bars 31. The said guide bars have each a collar 32 at one end, and a 45 nut 33 at the other end to hold them in place in the bosses 30. Cross bars 34 have formed therewith the lugs 35, and are secured into the lugs 36, the lugs 35 and 36 being supported on the longitudinal guide bars 31. A secondary sliding plate 40 has extending therefrom lugs 41, that are supported on the cross bars 34. The plate 40 has the knee 42, to

which is fastened the lower plate 43 of a clamping device for the material to be operated upon, by means of the screws 44, the 55 holes in the knee 42, being elongated to adjustably secure the plate 43. From the plate 43 extend pillow blocks 45, that have the journal pin 46, which carries the plate 47, and the latter has secured thereto the upper 60 plate 48 of the said clamping device. The plate 48 has an opening 49, and has secured thereto a spring 50 with the screws 51. A clamping block 52 is pivoted from prongs 53, extending from the spring 50. From the 65 plate 47 extend the pillow blocks 54, in which latter is journaled the lever 55, by means of the pin 56. The lever 55 has the openings 57 and 58 and can bear on the journaled end 59 of the plate 47. From the plate 43 extends 70 the column 60, around which is located the spring 61, that bears between the plate 47, and the nut 62 on the upper end thereof.

A journal bracket 63 is secured to the side of the bed plate 20 with the screws 64. The 75 said bracket supports a stationary shaft 65, with a collar 66 at one end, and a nut 67 at the other end. A bell crank 68 with the arms 69 and 70 is journaled on the shaft 65. The arm 69 has the forked end 71, that is 80 supported on a screw 72, extending from a collar 73, which latter is secured to the needle bar 74 of the sewing machine. The arm 70 is pinned to a pawl 75, with the hook end 76 that engages with the teeth 77 of a 85 ratchet wheel that is formed with or extends from the spur gear 78, and preferably has eight teeth. The said gear is journaled on a journal pin 79 screwed into the bed plate 20. A pinion 80 generally one fourth of the 90 diameter of the gear 78, meshes with the latter, and is formed with a sleeve 81 that is journaled on a pin 82, which latter is fastened to the bed plate 20. A screw 83 with head 84 is secured into the pin 82, and holds the 95 sleeve 81 from vertical displacement. The upper end of the sleeve 81 is formed with a guide 85 that carries a nut 86, into which is screwed a journal pin 87 for the link 28. A lug 88 extends from the bed plate 20, and it 100 has an opening 89, which forms a bearing for a swinging adjusting bar 90, that bears against the outer face of the guide 85. A post 91 extends from the bed plate 20, and a

spring 92 extends between said post and bar. A cap 93 with screws 94 is secured on the lug 88.

The main sliding plate 25 has an opening 5 for the vertical spindle 95, on the upper end of which is formed the gear 96, that meshes with the internal oval gear 97. The latter is formed of an oval ring that is located on the top face of the secondary plate 40. From 10 the said gear 96 extends a boss or roller 98, which bears against an oval projection 99, extending from the cover plate 100, which latter with the oval internal gear 97 is fastened in place to the plate 40 with the screws 15 101. The lower end of the spindle 95 has secured thereto the worm wheel 102, that meshes with the worm 103 of the worm shaft 104. The said worm shaft is supported in journal bearings 105 and 106, that extend 20 from the main sliding plate 25. A collar 107 on the worm shaft bears against the bearing 105, and a sleeve 127 is carried on the other end of the said worm shaft. To the sleeve 127 is pinned a pawl 108, that engages with a 25 ratchet wheel 109, a nut 110 holding said ratchet wheel in place. A pin 111 extends from the sleeve 127, and is straddled by a forked end 112, of a lever 113, that is journaled to a boss 114 extending from the bed 30 plate 20. The bed plate 20 has a suitable opening 115, for the operation of the worm shaft 104 with its appurtenances. The lever 113 has a knee 116 which is screwed to the feed arm 117 of the feed mechanism of the 35 sewing machine. The throat plate 118 of the sewing machine has a suitable opening 119, for the knee 116, and an opening 120 for the needle 121.

To operate the invention a piece of material 40 122 to be operated upon, is placed over an opening in the plate 43, the plate 48 having been raised by means of the lever 55. The clamping block 52 bearing on said material, holds it securely in place. The sewing machine is then started, and the needle bar 74 reciprocating actuates the arm 69 of the bell crank 68, and the arm 70 of said bell crank reciprocates the pawl 75. The latter engages with the teeth 77 of the ratchet 45 wheel, by means of which the spur gear 78 is intermittently rotated. The gear 78 drives the pinion 80, and consequently the pin 87, the axial line of which latter is out of line with the axis of the pinion. The pin 87 is 50 intermittently rotated around the axis of the pinion 80. The distance between the axis of the pin 87, and axis of the said pinion being adjustable, by clamping the nut 86 in different positions. The swinging adjusting bar 60 90, bearing against the face of the guide 85, secures equal amounts of rotation for the pinion 80, each time it is actuated by the spur gear 78. If the bar 90 is omitted the amount of rotation given to the pinion 80 by

the spur gear 78 may not always be the same, 65 on account of differences of friction between the parts connected with said elements, and also on account of the variable amounts of friction between said elements. The amount of rotation imparted to the said pinion may 70 also vary on account of the back lash between said pinion and said spur gear. The swinging adjusting bar 90 bearing against the outer face of the guide 85 forces the pinion 80 to be rotated equal amounts when 75 actuated by the spur gear 78, because should the face of the guide 85 be moved to an angular position with respect to the bar 90, the latter bearing against the same will turn it so that said face bears against said bar. The 80 equal amounts of rotation given to the said pinion is necessary to obtain equal lengths of stitches during the operation of the machine, and thereby controlling the uniformity of the 85 lengths of the stitches.

By the rotation of the pin 87, the pin 27 is reciprocated, by virtue of which the main sliding plate 25 is also reciprocated to an amount equal to the length of each stitch sewed for the button hole. During the reciprocation of the main sliding plate 25, the clamping block 52 with the material to be operated upon, is carried approximately in the path of an oval. The feed arm 117 swings the knee end 116 of the lever 113, and 90 by virtue thereof the forked end 112 of the lever 113 swings the pin 111 and the sleeve 127. The latter carrying the pawl 108, which engaging with the ratchet wheel 109, intermittently rotates the latter, and thereby 95 the worm shaft 104. The said worm shaft intermittently rotates the worm wheel 102, and hence the gear 96. The latter meshing with the oval internal gear 97 carries the latter by means of its form in an oval path, and 100 with it the secondary plate 40 and its appurtenances, that comprise the clamping device, and the material operated upon. The guide bars 31 and 34 allow the oval gear to move in a line parallel to the longitudinal axis of 105 the machine, and in all directions making angles therewith. The combined movements of the oval gear and the intermittent rotations of the pinion 80, bring the material in proper positions for the needle 121, to sew 110 the stitches of the button hole.

Having described my invention, I claim:

1. In a button hole sewing attachment for a sewing machine the combination of a frame, a main sliding plate thereon, a secondary sliding plate on the main sliding plate, connections between the needle bar of the sewing machine and the main sliding plate, connections between the feed mechanism of the sewing machine and the secondary sliding plate, and a clamping device to hold a material secured to a secondary sliding plate. 120
2. In a button hole sewing attachment for

sewing machines the combination of a main sliding plate, means to reciprocate the said plate, means to vary the length of said reciprocations, guide bars parallel to the directions of said reciprocations supported on the sliding plate, a secondary sliding plate over the main sliding plate, cross bars supported on the said guide bars and at right angles thereto, means to move the secondary plate on the cross-bars, and a clamping device to hold a material adjustably secured to the secondary plate.

3. In a button hole sewing attachment for sewing machines the combination of a bed plate, a main sliding plate on the bed plate, a link pinned to said main plate, a spur gear journaled on the bed plate, means to intermittently rotate the gear, a pinion meshing with the spur gear, a guide extending from the said pinion, a nut carried in the guide, a journal pin screwed into the nut to clamp the latter in various positions in the guide, one end of said link engaged by the journal pin, a swinging adjusting bar fulcrumed on a lug extending from the bed plate, the free end thereof bearing against the said guide, a post extending from the bed plate, a spring extending between the post and the said adjusting bar, a secondary plate carried on the main sliding plate, means to reciprocate the secondary plate in directions parallel to the direction of the movements of the main plate and at right angles thereto, and a clamping device secured to the secondary plate.

4. In a button hole sewing attachment for sewing machines the combination of a bed plate, a main sliding plate on the bed plate, means to reciprocate the main sliding plate, means to vary the lengths of said reciprocations, guide bars carried on the said main sliding plate, cross bars supported on the guide bars, a secondary sliding plate supported on the cross bars, a worm shaft journaled below the main sliding plate, a spindle supported on and journaled through the main sliding plate, a worm wheel secured to the lower end of the spindle meshing with the worm shaft, a spur gear extending from the upper end of the spindle, an oval internal gear carried on the secondary sliding plate, and meshing with the said spur gear, means to maintain the spur gear and internal gear in mesh, a sleeve carried on the worm shaft, a pawl secured to the sleeve, a ratchet wheel fastened to the worm shaft and engaged by the pawl, a pin extending from the sleeve, a lever fulcrumed to the bed plate of the said attachment, a forked end formed with the said lever straddling the said pin, the other end of the lever secured to the feed mechanism of a sewing machine, and a clamping device secured to the said secondary plate.

5. In a button hole sewing attachment for sewing machines the combination of a bed plate, a main sliding plate on the bed plate, means to reciprocate the main sliding plate, means to vary the lengths of said reciprocations, guide bars carried on the said main sliding plate, cross bars supported

on the guide bars, a secondary sliding plate supported on the cross bars, a worm shaft journaled below the main sliding plate, a spindle supported on and journaled through the main sliding plate, a worm wheel secured to the lower end of the spindle meshing with the worm shaft, a spur gear extending from the upper end of the spindle, an oval internal gear carried on the secondary sliding plate, and meshing with the said spur gear, a boss extending from the upper face of the spur gear, a cover plate on the said internal gear, an oval projection extending down from the cover plate, the said boss bearing against the said projection, means to turn the worm shaft, and thereby move the internal gear in an oval path, and a clamping device secured to the secondary sliding plate.

6. In a button hole sewing attachment for sewing machines the combination of a bed plate, a main sliding plate on the bed plate, means to reciprocate the main sliding plate, means to vary the lengths of said reciprocations, guide bars carried on the said main sliding plate, cross bars supported on the guide bars, a secondary sliding plate supported on the cross bars, a worm shaft journaled below the main sliding plate, a spindle supported on and journaled through the main sliding plate, a worm wheel secured to the lower end of the spindle and meshing with the worm shaft, a spur gear extending from the upper end of the spindle, an oval internal gear carried on the secondary sliding plate, and meshing with the said spur gear, means to maintain the spur gear and internal gear in mesh, a sleeve carried on the worm shaft, a pawl secured to the sleeve, a ratchet wheel fastened to the worm shaft and engaged by the pawl, a pin extending from the sleeve, a lever fulcrumed to the bed plate of the said attachment, a forked end formed with the said lever straddling the said pin, the other end of the lever secured to the feed mechanism of a sewing machine, and a clamping device secured to the said secondary plate.

7. In a button hole sewing attachment the combination of a bed plate secured to a sewing machine, a main sliding plate guided on the bed plate, a spur gear journaled on the bed plate, a ratchet wheel extending from the gear, a journal bracket extending up from the bed plate, a shaft supported in the journal bracket, a bell crank journaled on the shaft, one arm of said bell crank connected to the needle bar of the sewing machine, a pawl pinned to the other arm of the bell crank and engaging with the ratchet wheel to intermittently rotate the latter, a pinion journaled on the bed plate and meshing with the spur gear, connections between the main sliding plate and pinion to reciprocate the said main sliding plate, a secondary sliding plate on the

main sliding plate, means between the said secondary sliding plate and the feed mechanism of the sewing machine to move the latter in an oval path under the needle of the sewing machine, and a clamping device to hold a material to be operated upon, adjustably secured to the said secondary sliding plate.

Signed at the borough of Manhattan, city

of New York in the county of New York and State of New York, this 8th day of March 10 A. D. 1906.
